UNITED STATES PATENT OFFICE.

CHARLES H. F. KEENE, OF PHILADELPHIA, PENNSYLVANIA, ASSIGNOR TO CHARLES I. ROSENAU AND HERBERT B. LOEB, COPARTNERS TRADING AS ROSENAU & LOEB, OF PHILADELPHIA, PENNSYLVANIA.

LOOPING-MACHINE.

1,152,105.

Specification of Letters Patent. Patented Aug. 31, 1915.

Application filed November 19, 1914. Serial No. 872,918.

To all whom it may concern:

Be it known that I, CHARLES H. F. KEENE, a citizen of the United States, residing at Philadelphia, county of Philadelphia, and 5 State of Pennsylvania, have invented a new and useful Improvement in Looping-Machines, of which the following is a full, clear, and exact description, reference being had to the accompanying drawings, which 10 form a part of this specification.

In the knitting of stockings on circular knitting machines a circular web is knit to form the leg and that portion of the foot between heel and toe, while flat webs are knit 15 to form the heel and toe pockets. The heel pocket is closed in the knitting operation, but the toe pocket is left open and is subsequently closed on a looping machine. The latter comprises essentially a slowly rotat- 20 ing table carrying a brass ring in which are held an endless series of radially extending points upon which the operator loops the fabric some distance from the end thereof. Along the periphery of the ring are ar- 25 ranged successively a trimmer which severs the fabric along the line of looped stitches, a brush which removes fine particles of yarn produced in the trimming operation, and sewing mechanism which closes the toe 30 pocket. In these machines certain difficulties are encountered in the operation of the trimming devices and their adjustment, the short life and breakage of the trimming knives necessitating frequent and expensive 35 renewals. The brushes effect imperfect cleaning with resultant imperfect work by the sewing mechanism.

The object of my invention is to overcome 40 these objections. To that end, while I find no occasion to change the construction of the points and their supporting means or of the sewing mechanism, I have substantially re- 45 organized the construction and operation of the trimming devices and brushes.

A preferred embodiment of the invention 50 is shown in the accompanying drawings, in which—

Figure 1 is a plan view of the portion of the looping mechanism embodying my in- 55 vention. Fig. 2 is a section on the line 2—2 of Fig. 1. Fig. 3 is a section on the line 3—3 of Fig. 1. Fig. 4 is an elevation look- 60 ing in the direction of arrow 4, Fig. 1. Fig.

5 is an elevation looking in the direction of arrow 5, Fig. 1.

I shall first describe the construction and operation of my improved mechanism and shall then point out some of the substantial advantages which experience has shown is attained by the use of my improvement.

The circular table *a*, of which only a small section is shown, is recessed along its periphery to receive a flanged and recessed brass ring *b*, which is provided with radial grooves adapted to receive looping points *c*. Plates 65 *d* are confined within the annular recess in ring *b* and hold points *c* in place. Other plates *e* are secured to table *a* and engage a recess along the inner edge of ring *b*.

Ring *b* is rotated by any suitable means. 70 Thus in Fig. 3 a shaft *f* turns in a bearing *g* depending from the table and carries a pinion *i* which engages a rack *j* on ring *b*. A cover *h* inclosing the rack and pinion is se- 75 cured to table *a*.

Secured to table *a* is a bracket *k*, from which a forked block *m* is vertically adjustably supported by means of a threaded pro- 80 jection *n* on block *m* engaging a slot in bracket *k* and a nut *o* on projection *n* by which the block is clamped against bracket *k*. By means of screws *p* a knife-support *r* is secured to block *m*. Upon this support is arranged a stationary cutter or knife *s*, which in the direction of its length extends 85 radially, its cutting edge being along its inside end. Adjusting screws *t* extend through support *r* and engage the under side of knife *s* and a plate *u* (see Figs. 1, 3 and 4) overlies and engages knife *s* and also 90 extends into a groove in support *r* to which support the plate *u* is secured by a screw *t'*. By loosening screw *t'*, the knife may be ad- 95 justed up or down by means of screws *t*, after which the knife is held in its adjusted position by means of screw *t'*.

Turning in bearings in the forks of block *m* is a shaft *v* carrying a knife-support *w*, which is shaped approximately like a solid half-cylinder. Support *w* abuts against one 100 side of block *m* but not so tightly as to prevent it freely turning. The periphery of support *w* is recessed across part of its width and in the direction of its circumfer- 105 ence to receive the curved knife or cutter *x*. The outer face of the knife is substantially

flush with the support and is held in place by means of a plate y , which is retained against the support by means of screws z extending through plate y into the body of support w . The lower edge of knife x is 5 sharpened and, by oscillating back and forth on the axis of shaft v , co-operates with the cutting edge of stationary knife s to sever the loops of yarn carried by points c 10 in the turning movement of ring b .

The cutting edge of oscillatory knife x extends at a sharp angle to the periphery of the ring so that the cutting edges of the two knives co-operate in a manner similar to that 15 of the blades of a pair of shears. At the most outwardly extending edge of knife x the same is provided with a projection or guard x' which engages and slides upon the stationary knife s , thereby, in case of inaccurate adjustment of the cutters, preventing 20 the possibility of the two cutting edges striking and insuring that the cutting edge of knife x shall ride over the cutting edge of knife s in proper relation thereto.

The block m may be adjusted vertically 25 by means of screws 10 and 11 (see Fig. 4), each of which extends through an overhanging end on bracket k . One screw (10) abuts against block m and the other is in threaded 30 engagement with block m . If it be desired to adjust block m in an upward direction, nut o is first turned to free the block, then screw 10 is turned so as to cause its lower 35 end to rise from the block a distance equal to the height of adjustment desired, then screw 11 is turned to raise the block against screw 10, and then nut o is tightened. To adjust the block in a downward direction, nut o is turned as before, screw 11 is unscrewed to allow the block to move down to 40 the desired extent, then screw 10 is turned to press the block down and then nut o is tightened as before.

To oscillate shaft v and the oscillatory 45 knife carried thereby, the following means are provided. A driving shaft 20 is arranged outside the ring and has a disk 21 on which is radially adjustable a plate 22 carrying a crank pin 23 out of line with the 50 axis of shaft 20. From crank pin 23 extends a connecting rod 24, the end of which is bent to extend radially of table a and above the space between the forks of block m . To the end of rod 24 is pivoted on a 55 horizontal axis one end of an arm 25, the other end of the arm being threaded on a pin 26 extending from a hub 27 secured to shaft v . If the axis of shafts v and 20 were arranged in parallel relation, this connection 60 might be simplified, but as it is preferred to also drive the rotary brush (hereinafter described) from shaft 20, and as the axis of the brush is at an angle to the axis of shaft v , and as it is desirable to arrange shaft 20 and the axis of the brush in 65

parallel arrangement, this involves the angular relationship shown between the axes of shafts 20 and v , wherefore the special connection described is provided. It will be understood, however, that driving shaft 20 70 might be differently positioned relative to the axes of the brush and shaft v , involving different driving connections from shaft 20 that would not, however, involve any departure from the main features of my invention. 75

To remove the fine particles of fabric that adhere to the points after the cutting operation there is provided the brush 30 hereinbefore mentioned. The brush, together with 80 a pulley 35 secured thereto, turns loosely on a stud 31 secured in a holder 32 which is adjustably secured to block m by means of screws 33 engaging the block and extending through vertical slots in the holder. Another screw 34, extends into holder 32, its head resting upon block m . To vertically adjust holder 32, screws 33 are loosened and the holder adjusted up or down by means of screw 34, after which screws 33 are tightened 85 to maintain the holder in its adjusted position.

Pulley 35 is driven, through a belt 36, from a pulley 37 on shaft 20. In the rotation of the brush, the fine particles of fabric 90 are brushed from the points, throwing the particles away from the table into any conveniently arranged receiver.

In the operation of the machine the table is slowly turned, during which movement 100 the operator loops the fabric upon points c , placing successive loops extending across the fabric upon successive points. At the same time the shaft 20 is rotated, and preferably it is rotated at such speed that the knife x 105 will be given one complete oscillatory movement back and forth while the table has turned a distance equal to the space between two adjacent points. The relative speeds of rotation of the table and shaft 20 need not, 110 however, be so arranged, but I have found such relation to be an efficient one, as it requires that the knives shall sever only one loop in each oscillation of knife x . It will be understood that the machine does not 115 operate as a whole until its operation has continued for part of a revolution, so as to carry the fabric first looped successively past the knives, the brush, and finally under the sewing mechanism, which latter is not 120 herein shown, as it forms no part of my invention. Thereafter all parts of the machine are operative so long as the operator continues to loop the fabric upon the points. The cutting movement of the oscillatory 125 knife is radially outward, thus causing a portion of the fine particles of yarn to be thrown directly away from the machine.

The brush rotates at such a rate of speed 130 that each point is brushed with the utmost

thoroughness, so that the points and the fabric carried thereby are absolutely clean when they leave the brush.

The advantages of the foregoing construction may be summarized as follows: The rigidity of the oscillatory knife due to the solid construction of its support and the saddle bearing for its axle; the protection afforded to the points and the brass ring due to the construction and arrangement of the knives and the accuracy and certainty with which the knives may be held in position; the durability of the knives due to their shape and relative positioning and arrangement and also to the fact that the knife blades themselves are not perforated to receive holding screws and that each knife may be resharpened until its length is very very much reduced; the ease with which the knives may be adjusted both vertically and across the line of work; the arrangement whereby the movable knife has a cutting motion in a radially outward direction; the readiness with which the trimming mechanism may be taken down to get access to the points and then replaced without impairing the alinement of the parts; the high speed brushing action in a radially outward direction; the capacity to readily adjust the brush to the work; and the clearness of vision for the operator after the work leaves the brush in that the top of the machine and the stitch line is brushed clear of all fine particles of yarn.

Having now fully described my invention, what I claim and desire to protect by Letters Patent is:

1. In a looping machine, the combination with the annular row of looping points and means to rotate same, of a curved knife extending outward and downward and having an outer cutting edge, a support for the curved knife, means to oscillate the support, and a substantially flat knife having an inner cutting edge adapted to coöperate with the first knife.

2. In a looping machine, the combination with the annular row of looping points and means to rotate same, of a curved knife extending downward and outward and arranged to oscillate on an axis extending above and along the line of travel of the looping points at the trimming point, and a substantially flat knife extending in a radial direction and in a substantially horizontal plane the body of which extends outside the points and over the inner cutting

edge of which the cutting edge of the first knife is adapted to pass and trim the fabric looped on the points.

3. In a looping machine, the combination with the annular row of looper points, of a knife the body of which extends outside the points and the inner cutting edge of which overlies the outer ends of the points, an oscillatory knife adapted to coöperate with the first knife, a support upon which the first knife rests, a plate overlying the support and first knife, and means securing the plate to the support.

4. In a looping machine, the combination with the annular row of looper points, of a knife the body of which extends outside the points and the inner cutting edge of which overlies the outer edge of the points, a knife support, a plate overlying and engaging the knife and the support, a screw extending through the support and engaging the under side of the knife, and a screw by which the plate is secured to the support.

5. In a looping machine, the combination with the table and the annular row of looper points, of a block supported from, and vertically adjustable relatively to, the table, a horizontal shaft turnable in the block, means to oscillate the shaft, a knife-support turning with the shaft, an oscillatory knife carried by said support, a fixed support secured to the block and extending outside of and along the line of looped points, and a fixed knife secured to and extending inwardly from the fixed support and coöperation with the oscillatory knife to trim the fabric.

6. In a looping machine, the combination with the annular row of looping points, of a block, a shaft turnable therein, a knife support carried by the shaft, said support having a curved periphery recessed across part of its width and in the direction of its circumference, a curved knife inserted in said recess, a curved plate overlapping the knife and the unrecessed part of the support, means retaining the plate against the support and the knife and holding the latter in its recess, and a second knife coöperating with the first knife to trim the fabric.

In testimony of which invention I have hereunto set my hand, at Philadelphia, on this 16th day of November, 1914.

CHARLES H. F. KEENE.
